UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

VALVE.

1,352,036.

Specification of Letters Patent.

Patented Sept. 7, 1920.

Application filed April 29, 1918. Serial No. 231,374.

To all whom it may concern:

Be it known that I, WILLIAM A. SMITH, a citizen of the United States, residing at Easton, in the county of Northampton and State of Pennsylvania, have invented a certain new and useful Improvement in Valves, of which the following is a specification.

This invention relates to valves and in particular to a valve for air compressors which 10 is readily adapted with but slight modifications for either a discharge or inlet valve.

The objects of the present invention are to produce a valve for air compressors which will be simple, efficient and compact, which 15 may be made either with a single opening or port or a plurality of openings and which may be made up either as a discharge or inlet valve; and also, one in which the moving or valve element is made up of a flat strip 20 of spring steel bent into the form of an open ring the movement of which will permit an ample fluid opening through the valve with a very limited movement.

With the above and other objects in view 25 I have devised the valve construction, practical embodiments of which are shown in the accompanying drawings and described in the following specification.

In the drawings annexed hereto,

30 Figure 1 shows a cross sectional view through the valve and compressor cylinder walls;

Fig. 2, a view of the valve, viewed from below;

35 Fig. 3, a cross sectional view of the valve made up as an inlet valve;

Fig. 4, a view of the valve in Fig. 3 viewed from below; and

Fig. 5, a cross sectional view of a valve 40 having a plurality of valve seats and valve rings.

Referring more particularly to the drawings, 1 refers to the cylinder walls of an air compressor provided with the present form 45 of valve. Set into the walls 1 of the compressor at 2 is one of the valves 3 made in accordance with the present invention. The valve 3 is provided with a seat 4 having passages 5 entering the cylinder of the compressor and the outer end of the passages 5 intercepting the periphery of the valve seat 4 and are covered by a ring 6 loosely fitting around the periphery of the valve seat 4.

The ring 6 is retained in place by means of lugs 7 outstanding from the seat 4 and prevented from rotating by means of a pin 8 set into the seat and interposed between the extremities of the valve ring 6 as shown in Fig. 2. It will be seen that an annular passage, shown at 2, is provided in which the valve ring 6 moves, this passage limiting the expansive, contractile and lateral movement of the valve ring.

The valve ring 6 is made up of a flat strip of spring steel bent into the form of a ring 65 which will normally fit tightly against the seat 4 and around the passages 5 so that the passages 5 will be effectively closed when there is any greater pressure on the outside of the valve ring 6 than on the inside. The 70 valve ring 6 is, however, free to open when this pressure difference is reversed and admit or discharge fluid to or from the cylinder according to the manner in which the valve is made up. This pressure difference 75 to open the valve is very slight and is provided by the rush of fluid through the valve. The valve shown in Fig. 1 is a discharge valve permitting the fluid compressed to pass through the valve by means of the passages 5 to the discharge passage 9.

In Fig. 3 is shown the valve adapted as an inlet valve, the passages 10 extending through this form of the valve being connected to the inlet passage 11 and extending 85 to the valve ring 12, which is in every way similar to the ring 6 in Fig. 1.

In Fig. 5 is shown a valve made in accordance with the present invention in which a plurality of rings and valve seats 90 are utilized to increase the port areas. The valve shown in this figure is of the discharge type but it is obvious that this multiple form may be made up equally well as an inlet valve with the same advantage of 95 increased areas of fluid passages.

The valves as shown in each modification are conveniently retained in place in the walls of the cylinder by means of a cover plate 13 through which passes a screw 14 100 engaging and pressing into place the valve 3.

It is to be understood that while the present showing and description disclose only certain specific embodiments of the present 105 invention, other forms and modifications are

included within the spirit and scope of the invention as expressed in the appended claims.

What I claim is:

5. 1. In a valve for compressors, a valve body seated in a compressor wall, an annular seat on said valve body having a plurality of independent ports extending therethrough to a lateral face thereof, a resilient 70 ring surrounding said seat and covering said ports, said ring being adapted to expand away from said seat to open said valve and means providing an annular passage for limiting the expansive movement of the 75 valve.
10. 2. In a valve for compressors, a valve body seated in a compressor wall, an annular seat on said valve body having independent ports extending therethrough to a lateral face thereof, a resilient valve ring 80 surrounding said seat and covering said ports, said ring adapted to expand and contract in opening and closing of said valve, said ring abutting against the compressor wall, and lugs on the periphery of said valve body, whereby an annular passage is provided limiting the expansion, contraction 85 and lateral movement of the valve.
15. 3. In a valve for compressors, a valve body seated in a compressor wall, an annular seat on said valve body having ports extending therethrough to a lateral face thereof, said ports being arranged in annular formation around a solid central portion of said valve body, a resilient flat valve ring 90 surrounding said seat and covering said ports, said ring adapted to expand and contract in opening and closing of said valve, and means providing a passage for 95 limiting the expansion, contraction and lateral movement of the valve.
20. 4. In a compressor, a valve seat formed in a wall of the compressor, an annular surface provided in said wall, an annular valve body positioned on said annular surface, means for securing said valve body in fluid-tight relationship with respect to the compressor cylinder, a plurality of ports on the 100 annular edge of said valve body, a plurality of ports on a lateral surface of said valve body, passages in said valve body connecting the ports on the annular valve body surface with the ports on the lateral surface of said valve body, an open annular spring member forming a valve surrounding the annular surface of said valve body and adapted to expand and contract to uncover and cover the ports on said annular surface, and a plurality of lugs outstanding 105 from the periphery of said valve body for limiting axial movement of said valve spring on its seat on the annular valve body surface.
25. 5. In a compressor, a valve seat formed in a wall of the compressor, an annular surface provided in said wall, an annular valve body positioned on said annular surface, a cover plate secured in said compressor wall above said valve body, means in said cover plate for securing said valve body in fluid-tight 110
30. 6. In a compressor, a valve seat formed in a wall of the compressor, an annular surface provided in said wall, an annular valve body positioned on said annular surface, means for securing said valve body in fluid-tight relationship with respect to the compressor cylinder, a plurality of ports on the 115 annular edge of said valve body, a plurality of ports on a lateral surface of said valve body said latter ports being arranged in annular formation circumferentially of a solid central portion of said valve body, a plurality of independent passages in said valve body, each of said passages connecting one of the ports on the annular valve body surface with a port on the lateral surface of said valve body, one of said sets of independent ports opening directly into the cylinder of the compressor and the other to the discharge passage therefrom, an open annular spring member forming a valve surrounding the annular surface of said valve body and adapted to expand and contract to uncover and cover the ports on said annular surface, said valve spring abutting against the annular surface in the compressor wall forming the seat for the valve body, and means on the periphery of said valve body for limiting axial movement of said valve spring on its seat on the annular valve body surface.
35. 7. In a compressor, a valve seat formed in a wall of the compressor, an annular surface provided in said wall, an annular valve body positioned on said annular surface, a cover plate secured in said compressor wall above said valve body, means in said cover plate for securing said valve body in fluid-tight 120
40. 8. In a compressor, a valve seat formed in a wall of the compressor, an annular surface provided in said wall, an annular valve body positioned on said annular surface, a cover plate secured in said compressor wall above said valve body, means in said cover plate for securing said valve body in fluid-tight 125
45. 9. In a compressor, a valve seat formed in a wall of the compressor, an annular surface provided in said wall, an annular valve body positioned on said annular surface, a cover plate secured in said compressor wall above said valve body, means in said cover plate for securing said valve body in fluid-tight 130

relationship with respect to the compressor cylinder, a plurality of ports on the annular edge of said valve body, a plurality of ports on a lateral surface of said valve body, 5 said latter ports being arranged in an annular formation circumferentially of a solid central portion of said valve body, a plurality of independent passages in said valve body, each of said passages connecting one 10 of the ports on the annular valve body surface with a port on the lateral surface of said valve body, one of said sets of independent ports opening directly into the cylinder of the compressor and the other to the discharge passage therefrom, an open annular 15 spring member forming a valve surrounding the annular surface of said valve body

and adapted to expand and contract to uncover and cover the ports on said annular surface, said valve spring abutting against the annular surface in the compressor wall 20 forming the seat for the valve body, and a plurality of lugs outstanding from the periphery of said valve body for limiting axial movement of said valve spring on its seat on the annular valve body surface and forming 25 an annular passage for limiting the expansion, contraction and lateral movement of the valve spring.

In testimony whereof I have hereunto set my hand.

WILLIAM A. SMITH.
